UNITED STATES PATENT OFFICE

GUY H. BUCHANAN, OF WESTFIELD, NEW JERSEY, ASSIGNOR TO AMERICAN CYANAMID COMPANY, OF NEW YORK, N. Y., A CORPORATION OF MAINE

METHOD OF MAKING DITHIOPHOSPHATES AND COMPOSITIONS CONTAINING SAME

Application filed February 18, 1930. Serial No. 429,270.

The present invention relates to the manufacture of alkali metal salts of dithiophosphoric acids and more particularly the salts of the organic dithiophosphoric acids.

There has been described previously the manufacture of various organic dithiophosphoric acids and the salts thereof, which are used for various purposes, such as flotation reagents and the like. In the preparation of the salts of these acids, the usual method, of course, is to neutralize the acid in solution with an alkaline material also in solution, with subsequent evaporation of the water to obtain a solid product. Aside from the costly drying operation, the product so prepared is difficult to dry completely in view of the oily impurities usually contained in the commercial acid. Drying the solution also results in loss of product by decomposition and the color of the final product is affected.

It is one of the objects of the present invention to prepare the alkali metal salts of the organic dithiophosphoric acids in an economical and simple manner, obtaining a dry, white product which is comparatively free from lumps. Such lumps as may be present are broken up easily with the hands. Another object is to obtain salts and mixtures which are stable and which are substantially non-deliquescent.

These and other objects are attained by neutralizing the dithiophosphoric acid with a dry alkaline compound of an alkali metal, preferably using an excess of the alkali metal compound.

In the accompanying drawing constituting a part hereof,

Fig. 1 illustrates diagrammatically substantially the entire process and apparatus;

Fig. 2 is a more detailed diagrammatic view of a portion of the apparatus; and

Fig. 3 is a detailed diagrammatic view of another portion of the apparatus.

The production of the dithiophosphoric acid is carried out in reaction kettle 1 which is preferably a glass-lined, jacketed kettle provided with a stirrer or agitator 2, driven by suitable means 21. Using a kettle of about 100 gallon capacity, there is placed in

the kettle (from a source not shown) about 400 lbs. of previously prepared crude diethyl dithiophosphoric acid as a diluent or solvent. There is then charged into the kettle 1 through a conical steel hopper placed in a suitable manhole (not shown), 248 lbs. of phosphorus pentasulphide (91%), from storage bin 3, this material having previously been crushed to a maximum size of about $\frac{3}{8}$ ". The manhole cover (not shown) is clamped down and 206 lbs. of ethyl alcohol from storage container 4 is slowly run into the kettle 1. The cooling water in the kettle jacket must be so regulated that after all the alcohol is in, the final temperature of the mix is about 40° C. The stirrer 2 is rotated during the course of the addition. The kettle and contents are allowed to stand and cool overnight. The next morning the mixture is heated to 90° C., and the temperature kept there for 2½ hours with agitation, after which period, the mix is cooled down to room temperature. The crude acid so prepared is conducted to storage pot 5. If desired, a portion of the acid may be left in the kettle for further preparation of acid. As shown in somewhat more detail in Fig. 2, the kettle is provided with a suitable reflux condenser 6 to prevent loss of alcohol or other materials during the reaction. The procedure just described results in the production of about 400 lbs. of crude (86%) diethyl dithiophosphoric acid having a specific gravity of about 1.19.

To prepare the sodium salt of the acid, a suitable mixer 7 is charged with 200 lbs. of soda ash from storage bin 8. This soda ash should be as dry as possible and free from lumps. Acid from the storage pot 5 is drawn into aluminum blow case 9 and blown thence to feed pot 10. Thence it is run into the mixer 7 by gravity through a suitable aluminum or similar tube (not shown). Ordinarily the first 100 lbs. of acid is added at the full capacity of the feed mechanism. Stirrers 11 in mixer 7 are operated throughout the additions of the acid. The second 100 lbs. of acid are added more slowly and, in the event that the mixture becomes dark in color or tends to become sticky during addition of the acid, the

flow of acid is shut off while continuing stirring until light color and suitable dryness of material is restored, whereupon the addition of acid is continued. The time for the mixing operation generally varies between forty minutes and one hour, depending somewhat upon the dryness of the soda ash. The material coming from the mixer is the sodium salt of di-ethyl dithiophosphoric acid mixed with an excess of soda ash, and is in the nature of a substantially dry white powder. This material is preferably placed in a tray drier 12 and dried overnight at about 150° F. The dried product is screened in screening device 13 to remove the lumps which are ground in a mill 14, the fines from 13 to 14 being sent to storage bin 15. The final product has an iodine number between 29.5 and 30.5 and is well adapted for use as a flotation reagent. It has a white color and does not form objectionable lumps.

To obtain a higher grade product, it is sometimes advisable to add about 60% of the acid to the soda ash in mixer 7 and after a thorough mixing to remove the resulting product to drier 12 or a similar drier where it is maintained at a temperature of about 115° F. for about twenty hours. The dried material is then returned to the mixer and the additional 40% acid is added slowly with stirring. The alternate mixing and drying operations may be multiplied to any desired degree. The resulting product is a white or buff-colored powder containing a very small percentage of lumps which can easily be broken with the fingers. The material so prepared may be again sent to drier 12 and put through the succeeding steps in the process as previously described. In this method somewhat better yields are obtained and the product has a higher purity as well as other desirable characteristics.

While the preparation of sodium di-ethyl dithiophosphoric acid has been described in detail, other alcohols or alcoholic bodies may be utilized in preparing the corresponding organic dithiophosphoric acid by reaction with phosphorus pentasulphide. Thus we may prepare the di-methyl, di-isopropyl, di-normal butyl, di-secondary butyl, di-amyl, di-phenyl, di-cresyl, etc., dithiophosphoric acids. As a neutralizing agent we may use any of the alkaline compounds of the alkali metals such as potassium, sodium, or ammonium carbonates, hydrates, etc. The alkaline material is preferably used in excess and may be present to the extent of 200% in excess of that necessary to neutralize the acid. The mixture of alkali metal salt of the dithiophosphoric acid with an excess of the alkaline material is particularly valuable for use as a flotation reagent. This is partly due to its physical nature which permits storage, handling and use with facility and lack of decomposition. Also, in actual flotation, the presence of ex-

cess alkali assists materially the chemical action of the flotation agent.

Any suitable apparatus may be used in carrying out the various steps of the process since the elements described may be varied at will, the examples being given only for purposes of illustration.

Suitable changes in details of operation and materials used may be made without departing from the spirit and scope of the invention, except as stated in the appended claims.

What I claim is:—

1. The process of preparing alkali metal salts of organic dithiophosphoric acids which comprises intimately mixing an organic dithiophosphoric acid with a solid alkaline alkali metal compound by adding a portion of the acid to the compound, drying the mixture, and adding the remainder of the acid. 80

2. The process of preparing sodium salts of di-alkyl dithiophosphoric acids which comprises intimately mixing the acid with solid sodium carbonate in excess of the amount required for a complete neutralization of the acid. 85

3. The process of preparing sodium salts of di-alkyl dithiophosphoric acids which comprises intimately mixing the acid with solid sodium carbonate in the proportion of not more than 200% in excess of that required for 90 complete neutralization of the acid.

4. The process of preparing a sodium salt of di-ethyl dithiophosphoric acid which comprises intimately mixing 100 parts by weight of di-ethyl dithiophosphoric acid with 100 parts by weight of solid sodium carbonate, the acid being added to the sodium carbonate in several portions with a drying step between additions. 10

5. A composition comprising an alkali metal salt of an organic dithiophosphoric acid and a substantial quantity of an alkaline alkali metal compound. 11

6. A composition comprising an alkali metal salt of di-ethyl dithiophosphoric acid and a substantial quantity of an alkaline alkali metal compound. 1

7. A composition comprising a sodium salt of an organic dithiophosphoric acid and a substantial quantity of an alkaline sodium compound. 1

8. A composition comprising a sodium salt of di-ethyl dithiophosphoric acid and a substantial quantity of sodium carbonate.

9. A composition comprising a sodium di-ethyl dithiophosphate and sodium carbonate, the latter forming the major portion of the mixture.

10. The process of preparing compositions of alkali metal salts of organic dithiophosphoric acids suitable as flotation reagents which comprises intimately mixing an organic dithiophosphoric acid with a solid alkaline alkali metal compound. 12

11. The process of preparing compositions

of sodium salts of di-alkyl dithiophosphoric acids suitable as flotation reagents which comprises intimately mixing the acid with solid sodium carbonate.

- 5 12. The process of preparing compositions of a sodium salts of di-ethyl dithiophosphoric acid suitable as flotation reagents which comprises intimately mixing di-ethyl dithiophosphoric acid with solid sodium carbonate.
- 10 In testimony whereof, I have hereunto subscribed my name this 11 day of February, 1930.
